(57) **CLAIM**

The ornamental design for a webcam cover, as shown and described.

DESCRIPTION

FIG. 1 is a perspective view of a first embodiment of a webcam cover shown in a position of use, covering a webcam on an electronic device;

FIG. 2 is a perspective view thereof as used to clean a screen on an electronic device;

FIG. 3 is a front perspective view thereof;

FIG. 4 is a front elevational view thereof;

FIG. 5 is a right elevational view thereof;

FIG. 6 is a left elevational view thereof;

FIG. 7 is a top plan view thereof;

FIG. 8 is a bottom plan view thereof;

FIG. 9 is a rear elevational view thereof;

FIG. 10 is a front perspective view of a second embodiment of a webcam cover;

FIG. 11 is a front elevational view thereof;

FIG. 12 is a right elevational view thereof;

FIG. 13 is a left elevational view thereof;

FIG. 14 is a top plan view thereof;

FIG. 15 is a bottom plan view thereof; and,

FIG. 16 is a rear elevational view thereof.

The broken lines shown in the drawings are for the purpose of illustrating environment only that form no part of the claim.

FIGS. 3, 4, 7, 8, and 9 are shown with a symbolic break in the webcam cover's length. Any portion of the article between the break lines forms no part of the claim.

1 Claim, 8 Drawing Sheets
